US0D1048540S

(12) **United States Design Patent** (10) Patent No.: **US D1,048,540 S**
(45) Date of Patent: ** Oct. 22, 2024

(54) **AEROSOL GENERATOR**

(71) Applicant: **Nicoventures Trading Limited**,
London (GB)

(72) Inventors: **Jared Aller**, Winston-Salem, NC (US);
Ali Gallaher, London (GB); **Kang Min Kim**, London (GB); **Andy Vernal**, London (GB)

(73) Assignee: **NICOVENTURES TRADING LIMITED**, London (GB)

(**) Term: **15 Years**

(21) Appl. No.: **29/837,326**

(22) Filed: **May 4, 2022**

(30) **Foreign Application Priority Data**

(57) **CLAIM**

The ornamental design for an aerosol generator as shown and described.

DESCRIPTION

FIG. 1 is a top front perspective view of an aerosol generator showing the claimed design;
FIG. 2 is a bottom rear perspective view thereof;
FIG. 3 is a top view thereof;
FIG. 4 is a bottom view thereof;
FIG. 5 is a front view thereof;
FIG. 6 is a rear view thereof;
FIG. 7 is a left view thereof; and,
FIG. 8 is a right view thereof.
The broken lines in the drawings depict portions of the aerosol generator that form no part of the claimed design.

1 Claim, 8 Drawing Sheets
